UNITED STATES PATENT OFFICE.

GLENN J. BARRETT, OF GRAND RAPIDS, MICHIGAN, ASSIGNOR TO BARRETT CHANGER CO., OF CHICAGO, ILLINOIS, A CORPORATION OF ILLINOIS

COIN-DELIVERY MEANS FOR CHANGE-MAKING MACHINES AND THE LIKE.

1,238,736.

Specification of Letters Patent.

Patented Sept. 4, 1917.

Application filed October 18, 1915. Serial No. 56,546.

To all whom it may concern:

Be it known that I, GLENN J. BARRETT, a citizen of the United States, residing at 90 Scribner avenue, Grand Rapids, Michigan, have invented certain new and useful Improvements in Coin-Delivery Means for Change-Making Machines and the like, of which the following is a specification.

This invention relates to improvements 10 in coin delivery means for change making machines and the like.

The invention is applicable to any form of machine in which coins are selected from trays or receptacles and delivered by the 15 operator of the machine in making change.

The objects of this invention are:

First, to provide a machine in which the coins are delivered with great rapidity without danger of scattering the coins beyond 20 the delivery tray or receptacle.

Second, to provide such a means associated with automatic delivering devices whereby the coins will be effectively presented to the payee.

25 Further objects, and objects relating to details and economies of construction will definitely appear from the detailed description to follow.

I accomplish the objects of my invention 30 by the devices and means described in the following specification. The invention is clearly defined and pointed out in the claims. A structure embodying the features of my invention is illustrated in conjunction with 35 a change making machine in the accompanying drawing, forming a part of this specification, in which:

Figure I is a perspective view of a change making machine with my coin delivery 40 means in position.

Fig. II is a plan view of my coin delivery means, with a fragmentary part of the change making machine illustrated.

Fig. III is a detail vertical sectional view 45 through the internal coin chute and my improved coin delivery chute on line 3-3 of Fig. V.

Fig. IV is a detail developed sectional view taken on a line corresponding to the 50 curved line 4-4 of Fig. II.

Figs. V, VI, VII and VIII are detail transverse sectional views taken on corresponding lines of Fig. II.

Fig. IX is a detail sectional view taken

longitudinally through the coin delivery tray 14.

In the drawings similar numerals of reference refer to similar parts throughout the several views, and the sectional views are taken looking in the direction of the little arrows at the ends of the section lines.

Considering the numbered parts of the drawing, the change making machine 1 has the usual keyboard 2 and coin trays or tubes 3 with means for actuation by the said keys. 65 The coins are delivered from the machine through the chute 4, seen in Figs. I, II, III and V.

The chute 5 is of general curved form and has curved sides and a rounded bottom 6 and 70 is secured to the case 1 by screws 7 and 8 through ears 9 and 10 (see Fig. I). The discharge end of the chute is closed by a curved vertical wall 11, and a coin discharge aperture 12 is on the lower side where the 75 coins will be deflected downwardly by the said curved end wall 11.

The curved bottom 6 merges into the side walls at a varying angle (see Figs. V, VI, VII and VIII, which show cross sections) 80 so that a coin entering the chute from the machine may come rolling over a comparatively level bottom (see Fig. V) but the bottom immediately curves so that the coin in its advance assumes a more or less edge-wise position (see the coins 13 in Figs. VI, VII and VIII). The coin will be impelled by gravity against the outer curved surface and as it rolls along its deflection and the friction of its rolling edges will slacken 90 its speed so that it will drop down to substantially horizontal position at the discharge end and will strike gently against the outer curved wall 11 and drop into the tray 14 beneath.

This tray 14 has a downwardly and outwardly sloping bottom 15, as seen in the sectional view in Fig. IX. This tray 14 is preferably held in place by a screw 16 through an ear 17 or a plurality at the bottom thereof.

This particular form of chute prevents the coin by any possibility from rolling vertically on edge and it will automatically assume the positions indicated in Figs. VI, 105 VII and VIII. If the coin starts level it will be projected with sufficient force to get into the inclined position and roll down the chute

at the desired rate, and if it starts on edge it is carried and upset to the positions indicated. The coins will thus feed at the highest speed that is consistent with good service and the proper delivery of the coins into the delivery tray.

It is important that the end of the chute be curved so that the coin will come into gradual contact and be stopped without a likelihood of any rebound. Change makers usually deliver change for one dollar or less and the coins readily spread out for inspection in the tray 14 where they can be readily removed by the hand of the payee.

I have shown my improved coin delivery means in its most approved form, which I desire to claim specifically, and I also wish to claim the invention broadly as pointed out in the appended claims.

Having thus described my invention, what I claim as new and desire to secure by Letters Patent, is:

1. A coin delivery means comprising a chute of curved form with bottom curved in cross section at varying angles gradually decreasing to zero at the discharge end to regulate the angle of the coins and their even delivery, a curved wall at the discharge end of the chute with an outlet opening at the bottom, and a tray disposed beneath the chute to receive the coins.

2. A coin delivery means comprising a

chute having bottom and sides curving downwardly and laterally, the bottom of said chute having a pronounced inclination toward the inner side thereof at its entrance end, the inclination gradually decreasing toward its delivery end until at its delivery end the bottom of the chute is horizontal, the sides of said chute being extended beyond the bottom thereof and curved to form a coin arresting means and a coin delivery aperture, and a tray disposed beneath the chute with a forwardly and downwardly sloping bottom.

3. A coin delivery means comprising a chute having bottom and sides curving downwardly and laterally, the bottom of said chute having a pronounced inclination toward the inner side thereof at its entrance end, the inclination gradually decreasing toward its delivery end until at its delivery end the bottom of the chute is horizontal, the sides of said chute being extended beyond the bottom thereof and curved to form a coin arresting means and a coin delivery aperture.

In witness whereof, I have hereunto set my hand and seal in the presence of two witnesses.

GLENN J. BARRETT. [L. S.]
